UNITED STATES PATENT OFFICE.

JACOB HOFMANN, OF BROOKLYN, NEW YORK.

DESIGN FOR A STOOL.

SPECIFICATION forming part of Design No. 15,790, dated February 10, 1885.

Application filed August 12, 1884. Term of patent 7 years.

To all whom it may concern:

Be it known that I, JACOB HOFMANN, a citizen of the United States, and a resident of Brooklyn, in the county of Kings and State of New York, have invented and produced a new and original Design for Stools for Stores, of which the following is a specification, reference being had to the accompanying drawings, forming part thereof.

10 Figure 1 is a perspective view showing the top and edge of a stool. Fig. 2 is a side view, partly in section, of the same.

Heretofore store stools and seats have been made which presented, when viewed in elevation, as in Fig. 2, a plain outline or periphery, some having a center consisting of a perforated and bent veneer. In these the color of the veneer and seat is the same.

15 The leading feature of my design consists 20 in a stool having a circular seat of contrasting

shades of material, both the center and rim being in substantially the same plane, and the surface being flush with and a continuation of the same. Another feature is the circular bead-and-groove ornamentation on the surface, and the grooved and angular beading D 25 C upon the edge of the same.

I claim—

The design for a stool herein shown and described, the same consisting of a circular center of contrasting shades from the rest of the seat, ornamented with circular beads and grooves upon the surface and edge of the same. 30

Signed at New York, in the county of New York and State of New York, this 5th day of August, A. D. 1884.

JACOB HOFMANN.
